UNITED STATES PATENT OFFICE.

JOHN D. GREEN, OF YPSILANTI, MICHIGAN.

ANNEALING-OVEN.

1,360,932.

Specification of Letters Patent. Patented Nov. 30, 1920.

Application filed June 11, 1920. Serial No. 388,089.

To all whom it may concern:

Be it known that I, JOHN D. GREEN, a citizen of the United States of America, residing at Ypsilanti, in the county of Washtenaw and State of Michigan, have invented certain new and useful Improvements in Annealing-Ovens, of which the following is a specification, reference being had therein to the accompanying drawings.

10 The invention relates to annealing ovens and has for its object; first, the obtaining of effective heat insulation for the oven walls; and second, the construction of these walls of units, which may be easily assembled to 15 produce ovens of varying dimensions.

In the drawings:

Figure 1 is a perspective view of the oven;
Fig. 2 is a cross-section thereof;
20 Fig. 3 is a longitudinal section.
For the annealing of metals, such as tool steel, malleable iron, castings etc., it is necessary to provide an oven which will withstand the high heat of the articles when 25 first placed therein, which has sufficient strength to sustain the load and which is provided with heat insulation for retaining the heat for a long period. It is a known fact that a vacuum chamber furnishes effective heat insulation, but as such chambers are usually formed of glass, they are 30 inapplicable to annealing ovens. With my invention I have provided vacuum chambers in the walls of the oven without diminishing the mechanical strength of the structure. I have also provided a construction in which the walls are formed of separate 35 units. As shown, A is one of the unit sections formed of an outer wall B and an inner wall C parallel to the front and rear walls D and E and mitered edges F and G. In the construction of this unit the several 40 walls are properly formed by pressing or otherwise and are united to each other by welding so as to make an air tight structure. At the mitered edges there are provided 45 projecting flanges H which have registering apertures therein for the reception of clamping bolts.
50 Within the oven chamber is arranged a lining of refractory material, which as shown is formed of slabs K rabbetted to interlock with each other. One end of the oven chamber may be closed, either by a solid slab or preferably as shown by a hol-

low slab L, which also constitutes a vacuum chamber. At the front there is provided a door frame M to which is hinged a door N for closing the opening. Each of the units is provided with a nipple O containing a 60 valve and the arrangement is such that the air may be exhausted from the compartment by a vacuum pump connected to said nipple, the valve closing to prevent the filling of the chamber when the pump is removed. 65

Where the oven is designed to carry a considerable weight, there would be danger of the bending or distorting of the bottom thereof. To avoid this I have reinforced the bottom sections by the insertion of an 70 I-beam P therein.

In assembling the structure a number of units may be employed, according to the dimensions required and after these have been bolted to each other, the refractory 75 lining plates K are introduced. The end slab L is then secured to one end of the unit and the door frame M to the other and if desired, the refractory or heat insulating material may be placed between the frame 80 M and the adjacent oven sections to avoid heat losses therethrough. When the structure is complete, the heat in the work when first introduced into the oven will be retained for a relatively long period, so that 85 the cooling is very gradual and will give opportunity for a re-arrangement of the molecules so as to avoid stresses.

What I claim as my invention is:

1. An annealing oven comprising inner 90 and outer metallic walls sealed to form a vacuum chamber therebetween, and a refractory lining for protecting the inner wall.
2. An annealing oven comprising inner 95 and outer metallic walls forming a vacuum chamber therebetween, reinforcements for supporting the bottom of the inner wall, and a refractory lining for said inner wall.
3. An annealing oven formed of a plurality of units, each unit having an inner 100 and an outer wall sealed to each other to form a vacuum chamber therebetween and cooperating with adjacent units to form an oven chamber.
4. An annealing oven comprising a plurality of units having beveled ends for cooperating in the formation of an oven chamber, each unit comprising inner and outer walls sealed to each other to form a vacuum 110

chamber, and means for clamping the beveled ends of adjacent units to each other.

5. An annealing oven comprising a plurality of units, each consisting of an inner and an outer metallic wall and connecting flanges welded to form a sealed joint and a vacuum chamber between said walls, the end of said units being beveled and provided with flanges extending beyond the 10 same, and means for clamping the flanges of adjacent units in the formation of an oven chamber.

6. An annealing oven comprising a plurality of units, each unit having an inner 15 and an outer metallic wall spaced from each

other, and edge portions forming a sealed vacuum chamber, the opposite ends of said edge portions being mitered to coöperate with adjacent units in the forming of a rectangular oven chamber, and clamping means 20 for holding said units to each other.

7. An annealing oven comprising a plurality of units coöperating to form an oven chamber, each unit having inner and outer walls sealed to each other to form a vacuum 25 chamber, and means on each unit for exhausting the air therefrom to form said vacuum chamber.

In testimony whereof I affix my signature.

JOHN D. GREEN.
